CLAIM

The ornamental design for a griddle, as shown and described.

DESCRIPTION

FIG. 1 is a front, right-side top perspective view of a griddle, showing the new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front view thereof;

FIG. 7 is a rear view thereof;

FIG. 8 is a front, left-side top perspective view thereof;

FIG. 9 is an enlargement of area 9 in FIG. 2; and,

FIG. 10 is an enlargement of area 10 in FIG. 2.

The evenly-spaced broken lines depict parts of the griddle that form no part of the claimed design. The dot-dash broken lines depict the boundaries of enlargement areas and form no part of the claimed design.

1 Claim, 8 Drawing Sheets
